R. W. SCOTT,
WEB HOLDER FOR RIB KNITTING MACHINES,
APPLICATION FILED JULY 8, 1906.

901,839.

Patented Oct. 20, 1908.

UNITED STATES PATENT OFFICE.

ROBERT W. SCOTT, OF LEEDS POINT, NEW JERSEY, ASSIGNOR OF ONE-HALF TO LOUIS N. D. WILLIAMS, OF OGONTZ, PENNSYLVANIA.

WEB-HOLDER FOR RIB-KNITTING MACHINES.

No. 901,839.

Specification of Letters Patent.

Patented Oct. 20, 1908.

Application filed July 8, 1906. Serial No. 324,615.

To all whom it may concern:

Be it known that I, ROBERT W. SCOTT, a citizen of the United States, residing in Leeds Point, Atlantic county, New Jersey, have invented certain Improvements in Web-Holders for Rib-Knitting Machines, of which the following is a specification.

The object of my invention is to provide a rib knitting machine with web holders of such character that the "knocking over" of the stitches on the ribbing needles can be effected without the use of weights, draft rolls or like devices for imparting tension to the knitted web. This object I attain in the manner hereinafter set forth, reference being had to the accompanying drawings, in which

Figure 1 is a vertical sectional view of sufficient of a rib knitting machine to illustrate my invention; Figs. 2 and 2^a are plan views of part of the same, Fig. 3 is a view similar to Fig. 1, but illustrating another embodiment of my invention and Figs. 4, 5 and 6 are views of the web holders employed.

In the drawing, 1 represents the needle cylinder of the machine, 2 a needle dial, 3, 3^a the cylinder needles and 4 the dial needles, which may be operated in order to knit, by any suitable arrangement of cams in a cylinder cam box and dial cam ring.

The needle cylinder and dial may be the rotative members of the machine, and may operate in connection with a stationary cylinder cam box and dial cam ring, or the reverse of this arrangement may be adopted, the cam box and the cam ring being the rotative members and the cylinder and dial being stationary.

A set of reciprocating sinkers and web holders 5 operates in conjunction with the cylinder needles in the same manner as in previous machines of this class, but in the present machine I employ also a supplementary set of web holders 6, which operates in conjunction with the dial needles and by imparting tension to the sinker wales of a course in advance of that which is being drawn by the dial needles causes the "knocking over" of the stitches upon said dial needles without the necessity of weighting or otherwise imparting tension to the knitted web in the usual way.

The web holders 6 have stems or shanks 7 which are vertically guided in a cylinder 8 below the dial, reciprocating movement being

imparted to the web holders 6 by means of a cam ring 9 which surrounds the cylinder 8 and is secured to a central shaft 10 which is stationary in a machine having a rotating dial, or rotates in a machine having a stationary dial.

As the ordinary web holders 5 reciprocate in the same or substantially the same plane as the dial needles, they can have no direct effect in causing a knocking over of the rib stitches formed upon said dial needles, hence the employment of the supplementary web holders 6 for effecting this result.

During the production of ribbed web the web holders 6 alone are sufficient for the performance of the desired holding of the web, and the web holders 5 may, at such time, be rendered inoperative by proper adjustment of their actuating cams, but in a machine such as that which I have illustrated, which is intended for the production of either ribbed or plain web and has normally inactive cylinder needles 3^a in line with the dial needles, the use of the web holders 5 is necessary in order to effect the desired retention of the web during the knitting of plain fabric when the cylinder needles only are in operation, and at such time the supplementary web holders 6 may be rendered inoperative, if desired, by proper adjustment of their operating cams.

In that embodiment of my invention shown in Fig. 3 substantially the same construction is adopted, the only difference being that the web holders 6 are guided in grooves in an inverted conical bed 11, and are acted upon by a correspondingly shaped cam ring 12.

The web holders 6 act upon the sinker wales of a course of stitches in advance of that which is being drawn by the dial needles, being first raised and then depressed to engage said sinker wales at a point in advance of that at which the new stitches are drawn by the dial needles, the new sinker wales passing over the tops of said web holders 6.

When the web holders 6 are intended to engage single sinker wales, their hooked ends may be bent laterally, as shown in Fig. 2, but when each web holder 6 is intended to engage two sinker wales, its hooked end is forked, as shown in Fig. 2^a.

While I have shown my invention in connection with a circular knitting machine having cylinder and dial, and have selected a

particular type of such machine for the purpose of illustrating my invention, it will be evident that it is applicable to circular rib knitting machines of other types, or to machines having straight needle beds.

5 I claim:—

1. A rib knitting machine having two sets of web holders, one set operating in conjunction with the needles of one needle carrier, and the other set operating in conjunction 10 with the needles of the other needle carrier.

2. A rib knitting machine having two sets of web holders, one set operating in conjunction with the needles of one needle carrier, and the other set operating in conjunction 15 with the needles of the other needle carrier, and having movement in a direction trans-

verse to the direction of movement of said needles.

3. A rib knitting machine having two sets of web holders, one set operating in conjunction with the needles of one needle carrier, and the other set operating in conjunction with the needles of the other needle carrier to engage the sinker wales of a course of stitches 25 in advance of that whose stitches are being drawn by the said needles.

In testimony whereof, I have signed my name to this specification, in the presence of two subscribing witnesses.

ROBERT W. SCOTT.
